6 SHEETS—SHEET 2.

<img alt="A detailed technical cross-sectional diagram of a mechanical device, labeled Fig. 3. The diagram shows a complex assembly of various parts, including a central vertical column with a gear-like structure, a horizontal base, and various shafts and bearings. Numerous parts are labeled with numbers, such as 5, 23, 24, 29, 30, 32, 33, 34, 35, 36, 38, 49, 50, 52, 56, 58, 66, 70, 77, 82, 86, 87, 9, 10, 11, 12, 13, 14, 15, 16, 17, 25, 27, 34, 35, 37, 38, 44, 59, 67, 73, 76, 81, 88, 90, 91, 92, 93, 94, 95, 96, 97, 98, 99, 100, 101, 102, 103, 104, 105, 106, 107, 108, 109, 110, 111, 112, 113, 114, 115, 116, 117, 118, 119, 120, 121, 122, 123, 124, 125, 126, 127, 128, 129, 130, 131, 132, 133, 134, 135, 136, 137, 138, 139, 140, 141, 142, 143, 144, 145, 146, 147, 148, 149, 150, 151, 152, 153, 154, 155, 156, 157, 158, 159, 160, 161, 162, 163, 164, 165, 166, 167, 168, 169, 170, 171, 172, 173, 174, 175, 176, 177, 178, 179, 180, 181, 182, 183, 184, 185, 186, 187, 188, 189, 190, 191, 192, 193, 194, 195, 196, 197, 198, 199, 200, 201, 202, 203, 204, 205, 206, 207, 208, 209, 210, 211, 212, 213, 214, 215, 216, 217, 218, 219, 220, 221, 222, 223, 224, 225, 226, 227, 228, 229, 230, 231, 232, 233, 234, 235, 236, 237, 238, 239, 240, 241, 242, 243, 244, 245, 246, 247, 248, 249, 250, 251, 252, 253, 254, 255, 256, 257, 258, 259, 260, 261, 262, 263, 264, 265, 266, 267, 268, 269, 270, 271, 272, 273, 274, 275, 276, 277, 278, 279, 280, 281, 282, 283, 284, 285, 286, 287, 288, 289, 290, 291, 292, 293, 294, 295, 296, 297, 298, 299, 300, 301, 302, 303, 304, 305, 306, 307, 308, 309, 310, 311, 312, 313, 314, 315, 316, 317, 318, 319, 320, 321, 322, 323, 324, 325, 326, 327, 328, 329, 330, 331, 332, 333, 334, 335, 336, 337, 338, 339, 340, 341, 342, 343, 344, 345, 346, 347, 348, 349, 350, 351, 352, 353, 354, 355, 356, 357, 358, 359, 360, 361, 362, 363, 364, 365, 366, 367, 368, 369, 370, 371, 372, 373, 374, 375, 376, 377, 378, 379, 380, 381, 382, 383, 384, 385, 386, 387, 388, 389, 390, 391, 392, 393, 394, 395, 396, 397, 398, 399, 400, 401, 402, 403, 404, 405, 406, 407, 408, 409, 410, 411, 412, 413, 414, 415, 416, 417, 418, 419, 420, 421, 422, 423, 424, 425, 426, 427, 428, 429, 430, 431, 432, 433, 434, 435, 436, 437, 438, 439, 440, 441, 442, 443, 444, 445, 446, 447, 448, 449, 450, 451, 452, 453, 454, 455, 456, 457, 458, 459, 460, 461, 462, 463, 464, 465, 466, 467, 468, 469, 470, 471, 472, 473, 474, 475, 476, 477, 478, 479, 480, 481, 482, 483, 484, 485, 486, UNITED STATES PATENT OFFICE.

JOSEPH F. LOUGHREY, OF PHILADELPHIA, PENNSYLVANIA.

MULTICOLOR-PRINTING MACHINE.

1,349,895.

Specification of Letters Patent. Patented Aug. 17, 1920.

Application filed March 13, 1920. Serial No. 365,416.

To all whom it may concern:

Be it known that I, JOSEPH F. LOUGHREY, a citizen of the United States, residing in the city and county of Philadelphia, State 5 of Pennsylvania, have invented a new and useful Multicolor-Printing Machine, of which the following is a specification.

My invention relates to the class of printing machines or presses which employ different colors and in which a number of impression forms or chases of types are caused continuously to pass under an impression cylinder, prior to such passage the forms being supplied with the different colors.

15 My invention further relates to printing presses of the foregoing character in which the type beds are caused to travel in a continuous path, first, under inking rolls or kindred color-supplying devices, which supply them with inks of the desired color, and then beneath an impression cylinder.

25 Broadly expressed, it is the object of my invention to construct a machine in which the track or pathway of the printing beds is in the form of an ellipse having two straight parallel courses, one beneath the inking rollers and the other beneath the impression cylinder,—the courses being connected at their respective ends by semi-circular reaches.

30 A further object of my invention is an organization in which a plurality of type beds which carry the impression forms are themselves connected and combined with an other bed which may be termed an idle bed or spacer because during its passage beneath the printing cylinder said cylinder is doing no printing but delivering a printed sheet and taking on of a fresh sheet in a 35 manner which permits the attachment of a front or face-up delivery.

40 A further object of my invention is a construction by which the type beds come into registry with the printing cylinder successively and in conjunction with the idle bed.

45 A further object of my invention is so to construct the path of travel of the type beds that, in their turn around the semi-circular courses, the construction of the operative mechanism and its location relatively to the path of travel is such as to save space and time in the operation.

50 A further object is to so proportion the

length of the straight courses of the pathway of the type beds, as to permit of two beds of the plurality employed occupying one of the straight courses at the same time,—all of the beds, moreover, being so connected as to be in conjunction throughout their travel.

55 A further object is a construction in which a single driving gear imparts a continuous motion to all of the operative elements of the entire machine.

60 Further objects of my invention are such special constructions of the operative adjunctive parts as insure a uniform and steady operation of the printing press as an entirety.

65 For the purpose of illustrating my invention, I have shown in the accompanying drawings typical embodiments of it which are at present preferred by me since in practice they will be found to give satisfactory and reliable results. It is, however, to be understood that the various instrumentalities of which my invention consists can be 70 variously arranged and organized and that the invention is not limited to the precise arrangement and organization of these instrumentalities as herein shown and described.

75 In the drawings.

Figure 1 represents a top plan view of a multi-color printing press embodying my invention.

Fig. 2 represents a side elevation of the machine illustrated in Fig. 1, viewed from the under-side of said Fig. 1.

Fig. 3 represents a transverse section on line 3—3 of Fig. 1.

Fig. 4 represents a sectional plan, the section being taken on line 4—4 of Fig. 2.

Fig. 5 represents another sectional plan, the section being taken on line 5—5 of Fig. 3.

Fig. 6 represents a fragmentary bottom plan of a modified detail of the pathway of the type beds.

Fig. 7 represents a transverse sectional elevation of the modification represented in Fig. 6, the section being taken on line 7—7 of Fig. 8.

Fig. 8 represents a fragmentary sectional detail of the modification illustrated in Figs. 6 and 7, the section being taken on the line

8—8 of Fig. 7 and a part of the printing cylinder being also shown.

Fig. 9 represents an enlarged plan detail of the organization of the inking rollers illustrated in Fig. 1.

Fig. 10 represents a side elevational detail on line 10—10 of Fig. 9.

Figs. 11, 12, 13 and 14 represent end elevational details of the cams which occasion the desired and calculated rotation of the inking rollers, in the positions in which they are respectively secured to the cam shaft to occasion the successive and alternating lift and drop of the successively disposed inking rollers.

Fig. 15 represents an end elevational detail through a set of the inking rollers, the section being taken on the line 15—15 of Fig. 9 and the rollers being broken.

Fig. 16 represents a diagrammatic detail of a set of the inking rollers, the section being taken on the line 16—16 of Fig. 15.

Fig. 17 represents a side elevational detail of a mutilated gear device for insuring the dwell of the inking rollers during the passage of the idle type bed beneath the impression cylinder.

Similar numerals of reference indicate corresponding parts.

30 Referring to the drawings.

1 designates the bed plate of the machine which, of course, is of the desired dimensions.

Springing from the bed plate and centrally of it are two main standards 2 and 3 which support the impression cylinder 4 by bearings 5 for the shaft 6 of said cylinder.

The standard 2 is upon one side of the machine, the standard 3 is central, and a supplemental standard 7, also springing from the bed plate, is upon the side opposite to that occupied by the standard 2.

A horizontally disposed framework conveniently composed of frame bars 8 and 9, is shown as supported by being rested upon supports 10 for the bars 8, and 11 for the bars 9. Other supports 12 carry the inner trackways 13 upon which rest sets of carrying rolls 14, while the outer trackways 15, supported upon the supports 11—10, carry outer sets of rolls 16.

The foregoing frame construction is simply illustrative of a convenient means for carrying roller bearings upon which all of the type beds travel along their straight courses. The opposite end sets of rolls designated 17 are located at the semi-circular ends of the courses to support the type beds as they turn from one reach to another.

In the organization illustrated, four type beds, respectively designated 18, 19, 20 and 21 carry the chases of impression forms of types which receive, respectively, four different colors, and a fifth, or idle, type bed

22 is shown as intermediate of the beds 18 and 21,—constitute the assemblage or plurality of type beds which I am herein describing and, of course, they illustrate only one of the many pluralities which may be used.

These five type beds although not directly connected are yet so mounted and relatively disposed with relation to the inking and the printing devices as to be in essential, although not physical, end-for-end connection.

The means by which these type beds, which, as already described are mounted upon the roller-provided pathway frame work are conveniently operated to travel conjunctively and in succession beneath the inking mechanism and beneath the printing cylinder, is the following:—

23 designates a driving or power shaft actuated from any source of power and conveniently mounted in bearings 24, 25 and 26 in the standards 2, 3 and 7, and in intermediate bearings 27 and 28, (see Figs. 1, 2 and 3), longitudinally of the machine.

At its rear end the driving shaft is provided with a driving pinion 29 in mesh with a driven pinion 30 mounted upon a parallel countershaft 31 conveniently housed in a bearing 32 formed in the main standard 2. Upon the opposite end of the countershaft is a rack pinion 33 engaged with a rack 34 the teeth of which face upwardly, and which rack is secured to a carrying plate 35, one of which plates is secured to and depends from the bottom of each type bed, and in the travel of the beds through the straight reaches of the pathway passes through longitudinal slots 36 and 37 respectively formed in or between the frame bars 9—9 and 8—8.

As there is but one countershaft and that upon the rear side of the machine, it will be obvious that the upfacing racks 34 which are carried by each of the type beds come successively into engagement with the rack pinion 33 with the result that, because of the length of said racks 34, their ends meet when the type beds are traveling over the straight course of the framework below the printing cylinder.

In order to support the type beds, I find it convenient in the construction illustrated in Figs. 1 to 5 of the drawings, to connect each bed through its depending carrying plate 35 with the exterior face of an endless traveling band 38, see especially Fig. 5, which band itself travels over the periphery of a pair of band wheels 39 and 40 horizontally disposed upon vertical axes 41 and 42, the lower ends of which are stepped in bearings 43 and 44, see Fig. 2.

These band wheels being idlers subserve no purpose except to secure the relative connection of every one of the type beds of

the plurality which I use, and the entire travel or movement of the type beds, as already explained, is due to the operation of the rack pinion 33 on the countershaft 31, 5 driven by the driving shaft 23 through the meshing of the up-facing racks 34 which the type beds respectively carry.

Of course to a certain extent the endless band serves as a support for the type beds 10 but the real support and that which carries them is that afforded by the sets of carrying rolls 14, 16 and 17 already described.

In order to assure the correct turn of each 15 of the type beds as it enters upon the semi-circular course or reach at the end of its travel from out of and into the straight reaches, I provide segmental guides 45 and 46 horizontally disposed and suitably supported by carrying brackets 47 and 48 at 20 the respective ends of the framework.

By the contact of the outer ends of the straight depending carrying plates 35-36 with the inner segmental faces of these guides 45 and 46, the possibility of a twisting 25 of the type beds in making their turns is avoided.

In order to cause the type beds in their travel to operate the impression cylinder 4, I provide upon the sides of each type bed 30 an outer-rack 49 and an inner rack 50 the teeth of which face upwardly and are adapted in the travel of the beds to encounter respectively the driven rack pinions 51 and 52 on the ends of the impression cylinder 4, 35 as seen in Fig. 3.

Obviously, as each type bed travels beneath the impression cylinder, its racks will cause the rotation of the cylinder in the desired direction and at the desired speed.

40 Inasmuch as the cylinder racks 49 which are upon the outside of the type beds are of greater length than the cylinder racks 50 which are upon the inner side of each type bed, as will be understood from Figs. 1 and 45 4, there will always be contact between the longer or outside racks 49 with the cylinder rack pinion 51, when the type beds to which said racks are applied to straighten out, and, therefore, as each bed in turn travels away 50 from beneath the impression cylinder and its outer rack 49 passes from contact with the outer pinion 51 of said cylinder, the outer rack 49 of the succeeding type bed will come into contact with said pinion and cause 55 its continuing rotary movement to continue the rotation of the cylinder.

The impression cylinder 4 the rotation of which is effected by the operation of the type beds as above described, may be of any 60 usual type and in itself forms no part of my invention.

The cylinder is operated in connection with the usual feed table 53 and the usual delivery board 54, and the paper feed may 65 be of any usual character, gripping fingers

of the usual character retaining the paper stretched across the working surface of the cylinder in the usual way.

In the operation of the machine the calculation of the gearing is such that one complete rotation of cylinder takes place in connection with the passage beneath it of each one of the type beds.

The impression forms to be coated receive at one rotation of the proper inking rolls 75 the desired color. Thus, the first color, which may be red, is deposited on the form carried by the type bed 18; the next color, which may be blue, is deposited on the form carried by the type bed 19; the next color, 80 which may be yellow, is deposited on the form carried by the type bed 20, and the last color, which may be green, is deposited on the form carried by the type bed 21, (see Fig. 4.)

85 Each of these beds 18, 19, 20 and 21, passes in turn beneath the impression cylinder, in turn to print the paper, and when, finally, the idler type bed 22 passes beneath said cylinder, the dwell of the inking rolls, later on explained, affords the time necessary to remove the sheet printed with the four colors as explained and to replace such sheet with an unprinted sheet,—such time being equal to the period of the passage of said 90 idler type bed beneath said cylinder.

This feature is of importance because, as already described, it makes possible the delivery of the printed sheet and the putting in place of a sheet to be printed permitting 100 of the attachment of a front or face up delivery.

Except for its operation in conjunction with the type beds which carry the colored impression forms or chases and its further 105 operation in connection with the idle type bed,—the combined operation being new with me,—the impression cylinder in itself forms no part of my invention and may be of any character and, of course, of any 110 desired dimensions.

In connection with my plurality of printing beds and an idle type bed, it is, of course, necessary to provide a means operative in conjunction with the means for occasioning 115 the travel of said type beds, for applying ink to the impression forms, and for applying it by inking devices supplied with inks of different colors and operative successively with the forms.

To accomplish these results, I make use of a simple form of separate sets of inking rollers separately fed with the desired inks by any preferred means common in the art, and in order that each inking device may 125 be operative in the proper succession and independently of the others in the plurality employed, and also that all may cease their operation when the idle type bed is passing beneath the printing cylinder, I resort to 130

the following mechanism which it is to be distinctly understood, however, is not the only one which can be employed.

At the end of the driving shaft 23 opposite to that which carries the driving pinion 20, I mount a toothed pinion 56 in mesh with a differential gear pinion 57 which carries a sprocket pinion 58 over which extends a sprocket chain 59 which, as illustrated in Fig. 2, passes over a series of sprocket pinions 60, 61, 62 and 63 respectively mounted on the outer ends of the shafts 64, 65, 66 and 67, (see Fig. 9), of a series of inking rollers 68, 69, 70 and 71, which respectively receive or are fed with the desired inks, and which are ordinary steel rollers mounted in side frames 72, (see Fig. 10) which house between them, and beneath the said inking rollers, type rollers, as I term them, of rubber or kindred material, two to each inking roller, so as to form together with it an inking device.

Each of these sets of inking rollers, best seen in Fig. 9, but also illustrated in Fig. 1, is mounted in a quadrangular carrying frame 74 by means of suitable bearings designated as to all of them 75.

Each of these bearings 75 is a vertically slotted housing, see Fig. 15, in which the roller shaft which it carries is adapted to have vertical movement, or lift or drop, which movement is occasioned by supporting the shafts by brackets 76 of which there are two on each side of each set of inking rollers, as illustrated in Figs. 9 and 10, and which are also connected from opposite sides by connecting rods 77 one to each set of rollers, and which connecting rods are respectively provided at their outer ends, in the construction shown, with what I call lifting rods 78, 79, 80 and 81.

At their outer ends these lifting rods respectively bear upon peripheral cams 82, 83, 84 and 85, mounted upon the inner end of the shaft 6 of the impression cylinder 4, as shown in Fig. 9.

The set or mounting of the cams of this series is such as will be understood from Figs. 11, 12, 13 and 14, each of the cams as to a predetermined segment of its periphery being formed with a flat face which in the assemblage and timing arrangement of the cams occupies an upper position in a horizontal plane, and upon which the lifting rod of the set of rollers which the cam under consideration operates with rests when the set is down and inking an impression form.

In other words the positioning is such that when, for instance, the cam 82 of Fig. 11 upon which travels the lifting rod 78 of the set of inking rollers typified by 68, occupies the position shown, said set of inking rollers will have been dropped at a time calculated with respect to the calculated travel of the first of the type beds for in-

stance the bed 18, so that the impression form carried by said bed will receive an ink, assumedly red, supplied by said set of rollers.

When the cam 82 is in the position just described, the cams 83, 84 and 85 will occupy the positions illustrated respectively in Figs. 12, 13 and 14, in which position, as is obvious, each one of the sets of rollers typified by 69, 70 and 71 will be lifted and in the travel of the type beds 19, 20 and 21 and the rotary movement of the shaft 6 on the impression cylinder, will only be caused to descend by such rotary movement of said cams 83, 84 and 85 as will successively bring 80 their respective flattened peripheries beneath the respective lifting rods with which they operate.

After all four of the sets of inking rollers in the organization illustrated have successively inked the impression plates of the successive traveling type beds,—as, beginning with 18, then 19, then 20, then 21,—and when all of these four type beds shall have passed beneath the impression cylinder,—90 there will, as already explained, then pass beneath it the idle type bed 22.

Inasmuch as during the passage of said idle bed beneath the cylinder there will be no further immediate occasion for the operation of the sets of inking rollers to cause the inking of the impression plate of the type bed which follows said idle bed,—it is obvious that some means must be provided for, for the time being, occasioning the cessation of the operation of the lifting and dropping of the succeeding set of inking rollers.

This means may be varied, but a convenient device for effecting the result will be to provide at the inner end of the shaft 6 of the impression cylinder, a mutilated toothed wheel 86, on the inner end of the cylinder shaft 6, see Figs. 3 and 17, which is in engagement with a toothed pinion 87, 100 mounted below it, so that during a part of the rotary movement of the mutilated toothed wheel no rotation of the toothed pinion 87 will be effected, and in consequence there will be no lifting and dropping 110 of the sets of inking rollers during the entire period of the passage of the idle type bed beneath the printing cylinder.

Referring to the modification illustrated in Figs. 6, 7 and 8, I construct the pathway of the type beds,—while in the form of two parallel straight courses with connecting semi-circular end turns corresponding to the pathway illustrated in Figs. 1, 2, 3, 4, and 5,—as a runway designated 88, instead of as a framework carrying trackways, band wheels and an endless band to drive all of the type beds,—and provide the under surface of the type beds with rollers 89 which travel in the runway, are connected with the 130

type beds by being mounted on roller shafts 90 depending from said type beds and connected conveniently with each other by clevises 91, as shown in Fig. 7.

5 Apart from this construction of the pathway, that of the other elements which in their assemblage constitute my machine, is the same as in the construction of the first five figures; and while I have designated 10 the modified form of pathway by the numeral 88, the numerals which are applicable to the other elements of the organization are the same as those used in the first five figures.

15 It will now be apparent that I have devised a new and useful construction of a multi-color printing machine which embodies the features of advantage enumerated as desirable in the statement of the invention and the above description, and while I have, in the present instance, shown and described a preferred embodiment of it which will be found in practice to give satisfactory and reliable results, it is to be understood that the same is susceptible of modification in various particulars without departing from the spirit or scope of the invention or sacrificing any of its advantages.

Having thus described my invention, 30 what I claim as new and desire to secure by Letters Patent, is:

1. In a multi-color press, the combination of a pathway embodying two straight reaches and two curved connecting end reaches,—a plurality of traveling type beds which carry impression forms and are adapted to travel consecutively throughout the pathway,—an idle type bed which carries no impression form but which is in the line between two consecutive beds which carry impression forms,—an impression cylinder,—means for inking the impression forms consecutively with the desired color,—and means for occasioning the continuous travel of all of the type beds first beneath said inking means and then beneath said impression cylinder.

2. In a multi-color press, the combination of a pathway embodying two straight reaches and two curved connecting end reaches,—a plurality of traveling type beds which carry impression forms and are adapted to travel consecutively throughout the pathway,—an idle type bed which carries no impression form but which is in the line between two consecutive beds which carry impression forms,—an impression cylinder,—means for inking the impression forms consecutively with the desired colors,—means for occasioning the continuous travel of all of the type beds beneath said impression cylinder,—and means for halting the operation of the inking means during the time when the idle type bed is 65 passing beneath them.

3. In a multi-color press, the combination, of a pathway embodying two straight reaches and two curved connecting ends reaches,—a plurality of traveling type beds which carry impression forms and are adapted to travel consecutively throughout the pathway,—an idle type bed which carries no impression form but which is in the line between two consecutive beds which carry impression forms,—an impression cylinder,—operative mechanism carried by all of the type beds for occasioning the rotation of the impression cylinder,—means for inking the impression forms consecutively with the desired color,—operative mechanism carried by the impression cylinder for occasioning the desired operation of the inking means,—means for occasioning the continuous travel of all of the type beds first beneath said inking means and then beneath said impression cylinder,—and means for halting the operation of the inking means during the time when the idle type bed is passing beneath them.

4. In a multi-color printing press, the combination of a plurality of type beds disposed in end for end succession and each provided with an impression plate or printing form,—an idle type bed intermediate of two of the foregoing type beds,—a type bed supporting frame work embodying two parallel straight reaches curvedly connected at their ends, upon which all of the type beds travel in continuous succession,—an impression cylinder superposed above one of the straight reaches of the carrying frame,—means connected with and operated by the type beds for occasioning the predetermined rotary movement of the impression cylinder,—and means superposed above the other of the straight reaches of the framework and operated by the impression cylinder, for applying inks of different colors to a given succession of the type beds which carry the impression plates and for omitting to apply ink to the idle type bed.

5. In a multi-color printing press, the combination of a plurality of type beds disposed in end for end succession and each provided with an impression plate or printing form,—an idle type bed intermediate of two of the foregoing type beds,—a type bed supporting frame work embodying two parallel straight reaches curvedly connected at their ends, upon which all of the type beds travel in continuous succession,—guiding devices for directing the course of the travel of all of the type beds around the curved connections of the straight reaches of the supporting frame work,—an impression cylinder superposed above one of the straight reaches of the carrying frame,—means connected with and operated by the type beds for occasioning the predetermined rotary movement of the impression cylinder,—and

means superposed above the other of the straight reaches of the framework and operated by the impression cylinder for applying inks of different colors to a given succession of the type beds which carry the impression plates, and for omitting to apply ink to the idle type bed.

6. In a multi-color printing press, the combination of a plurality of counterpart type beds disposed in successive but independent relation and each provided with an impression plate or printing form,—an idle type bed intermediate of two of the foregoing type beds and of counterpart form,—a 15 supporting frame work embodying two parallel straight track ways curvedly connected at their ends, on which all of the type beds travel in continuous succession,—pluralities of carrying rollers superposed upon the 20 track ways upon which the type beds travel,—guiding devices for directing the course of the travel of all the type beds around the curved connections of the track ways,—an impression cylinder superposed 25 above one of the straight reaches of the track ways,—connective mechanism carried and operated by the type beds for occasioning the continuous rotary movement of the impression cylinder,—a plurality of inking devices 30 superposed above the other of the straight reaches of the track ways,—connective mechanism between the impression cylinder and the inking devices to operate said inking devices successively so as to apply inks of 35 different colors one after another to the type beds which carry the impression plates, and

for permitting the idle type bed to pass beneath all of inking devices without receiving ink therefrom.

7. In a multi-color printing press, the 40 combination of a plurality of type beds disposed in end for end succession and each provided with an impression plate or printing form,—an idle type bed intermediate of two of the foregoing type beds,—a type bed 45 supporting frame work embodying two parallel straight reaches curvedly connected at their ends, upon which all of the type beds travel in continuous succession,—a pair of horizontally disposed band wheels peripherally concentric with the curvedly connected ends of the supporting frame work,—an endless band to which all of the type beds are connected and which travels over said band wheels,—an impression cylinder superposed 50 above one of the straight reaches of the carrying frame,—means connected with and operated by the type beds for occasioning the predetermined rotary movement of the impression cylinder,—and means superposed above the other of the straight reaches 55 of the framework and operated by the impression cylinder, for applying inks of different colors to a given succession of the type beds which carry the impression plates, and 60 for omitting to apply ink to the idle type bed.

JOSEPH F. LOUGHERY.
